George Cooper

By his Attorney

Walter Goffredo.

UNITED STATES PATENT OFFICE

GEORGE COOPER, OF ANSONIA, CONNECTICUT.

PENCIL-SHARPENERS.

1,225,412.

Specification of Letters Patent.

Patented May 8, 1917.

Application filed April 1, 1916. Serial No. 33,344.

To all whom it may concern:

Be it known that I, GEORGE COOPER, a citizen of the United States, residing at Ansonia, in the county of New Haven and State of Connecticut, have invented a certain new and useful Improvement in Pencil-Sharpener, of which the following is a specification.

My invention relates to pencil sharpeners but more particularly to those in which the sharpening instrumentalities are inclosed within a shell or casing, and its object is to provide a device of this character so constructed and arranged that it may be readily carried on the person. A further object is to provide an opening in the wall of the casing for the passage of the pencil during the sharpening operation which opening can be closed when the device is not in use thereby preventing the escape of the pencil, dust or cuttings.

I attain these and other objects of my invention in the preferred embodiment thereof set forth in the following description and accompanying drawings in which like reference characters refer to corresponding parts.

In the drawings:

Figure 1 is a face view of my device a part 30 of the shell or casing being shown broken away;

Fig. 2, a sectional view taken on line $x-x$ in Fig. 1;

Fig. 3, a transverse sectional view of the 35 socket member;

Fig. 4, a face view of the disk in which the socket member is mounted;

Fig. 5, a side view of the casing showing the interlocking relation between the cup 40 and cover, and

Figs. 6 and 7, detail views of a modification.

The casing, which resembles a shallow round tin box, is formed out of sheet metal and consists of a cup A and a cover B. The cup A has a bottom wall or floor 2 and a cylindrical side wall 3, provided with a circular aperture 4 diametrically opposite which is riveted an outwardly projecting stem 5 carrying a head 6 in which is journaled a ring 7. Where the stem 5 bears against the wall 3 it is slotted to form a neck 8. The reduced portion of the stem which passes through the wall 3 55 also passes through the blade spring 9 before it is headed by the riveting operation.

The cover B has a top wall 10 and a cylindrical wall 11 the edge of which is recessed to form a bayonet slot 12 diametrically opposite which is an aperture 13. When the cover B is slipped over the cup A to close the casing, the neck 8 of the stem 5 enters the vertical portion of the slot 12 and the aperture 13 in the wall of the cover registers with the aperture 4 in the wall 35 of the cup. By turning the cover slightly relatively to the cup the neck 8 of the stem 5 enters the horizontal portion of the slot 12 thereby locking the cup and cover together and simultaneously closing the aperture 4. Suitably mounted in the casing, in a manner which will hereinafter appear, is a socket member made out of soft metal in the form of a flat tapering block 14 which latter is recessed to form a conical socket 15 75 for receiving the pointed extremity of the pencil. The wall of the socket is provided with a longitudinally disposed slot or opening 16. The block 14 is cut away on one side of this opening to form a seat 17 for the 80 blade 18 the cutting edge of which latter extends into the socket in a manner well known in pencil sharpeners. The blade 18 is removably secured in its seat by a screw 19 which passes through the transversely disposed slot 20 thereby enabling the blade 18 to be adjusted in its seat. The sides of the block 14 are provided along the lower edges with ridges or slides 21, 21. The disk shaped frame 22, on which the block 14 is mounted, is formed to fit inside the bottom of the cup B and is suitably slit and bent to form the stop 23 and the converging flanges 24, 24. To assemble the parts the block 14 is secured to the disk 22 by sliding 90 it toward the stop 23 between the flanges or ways 24, 24, which latter engage the slides 21, 21 and hold the block down on the base. The base is then inserted into the cup 100 and is held against rotary movement by the engagement of the lower extremity of the blade spring 9 with the recess 32 in the plate. When thus assembled the open end of the socket registers with the aperture 4 in the side of the cup. The cover B is then slipped over the wall 3 of the cup so that its stem 5 will enter the vertical portion of the bayonet slot 12 in which position the aperture 4 registers with the aperture 13. The pointed end of the pencil may now be 110 passed through the apertures 13, 4 into the conical socket 15 and be sharpened by rotat-

ing the cup on its diametrical axis. After the sharpening operation is completed the cover B is then rotated relatively to the cup A the neck 8 of the stem 5 entering the horizontal portion of the bayonet slot. In this manner the cup and cover are not only locked together but the aperture 13 in the wall of the cover is brought out of alinement with the aperture 4 in the wall of the cup thereby 10 closing the aperture 4 and preventing the cuttings and dust which have accumulated during the sharpening operation from escaping from the casing. When it is desired to remove the cuttings the casing may be opened 15 by lifting off the cover B. The cup and cover when the casing is closed are sufficiently tight to hold the cover on the cup in whatever position the cover is turned relatively to the cup. The head and ring have 20 their obvious uses such as being a means for attaching the casing to a key ring or hanging the same upon a hook. These elements are not necessary, however, since when the casing is made without them the close fit between the cover and cup serves to hold the 25 same together. It should be noticed that the seat for the blade necessarily makes the socket member considerably wider than its height, so that for the purpose of compactness it is disposed diametrically of the cup which latter may be extremely shallow since 30 no projections are necessary above and below the socket. In practice the casing is about the size of a gentleman's watch so that it can be readily carried in the same manner 35 as a watch. While my sharpener possesses numerous attractive features which will readily suggest themselves when the device is put to its various uses, yet the same is 40 particularly designed for school children since it enables them to sharpen pencils while in the school room and retain the cuttings in the casing until an opportune time arrives for disposing of them.

45 In Fig. 6 I have shown a modified form of socket member and blade in which the socket member 25 is provided with a conical recess 26 about a quarter of which is cut away by shouldering the block to form a 50 seat 27 on which is secured a sheet metal

blade 28 having its front portion curved to conform to the shape of the conical socket and its edge 30 bent inwardly into the socket. This blade is provided on its back edge with a flange 31 which serves as a shoulder for 55 seating the blade in its proper position relatively to the socket.

Having now described the preferred form of my invention it is obvious that the same is susceptible to such modification as may fairly come within the scope of the appended claims.

Having now described my invention what I claim and desire to protect by Letters Patent is:

1. A pencil sharpener comprising a pair of oppositely disposed circular cups each of which is provided with a lateral opening, and a socket member provided with sharpening instrumentalities disposed transversely 70 of one of said cups so that the open end of the socket is in back of said opening in the latter, one of said cups being sleeved upon the other whereby both of said openings may be brought into alinement to permit the insertion of a pencil point into said socket.

2. In a device of the character described a circular casing having an opening in its peripheral wall for the insertion of a pencil point, a socket member provided with sharpening instrumentalities disposed transversely 80 of said casing and having its open end in back of said opening, and means mounted to slide circumferentially on said wall for closing said opening.

3. A pencil sharpener comprising a pair of oppositely disposed circular cups each of which is provided with a lateral opening, a socket member provided with sharpening instrumentalities disposed transversely 90 of one of said cups so that the open end of the socket is in back of the opening in the latter, one of said cups being sleeved upon the other whereby both of said openings may be brought into alinement and means for locking said cups together when said openings are out of alinement.

In testimony whereof I have hereunto set my hand this 31st day of March, 1916.

GEORGE COOPER.
